GEORGE ALGER PENNOCK, OF OAK PARK, ILLINOIS, ASSIGNOR TO WESTERN ELECTRIC COMPANY, INCORPORATED, OF NEW YORK, N. Y., A CORPORATION OF NEW YORK.

VAPOR AND FUME CONTROLLING SYSTEM.

1,254,725.

Specification of Letters Patent. Patented Jan. 29, 1918.

Application filed August 16, 1916. Serial No. 115,207.

To all whom it may concern:

Be it known that I, GEORGE ALGER PENNOCK, a citizen of the United States, residing at Oak Park, in the county of Cook and State of Illinois, have invented certain new and useful Improvements in Vapor and Fume Controlling Systems, of which the following is a full, clear, concise and exact description.

10. This invention relates to a vapor and fume controlling system, and more particularly to a system of this kind in which the vapor or fume emitting substances are kept in open containers such as are used in metal 15 cleaning and plating processes. The object of the invention is to provide a system whereby the vapors or fumes which rise from open containers will be directed into a fume exhaust and will not be dissipated 20 in the room in which the containers are located.

In the commercial treatment of metals for the application of finishes large heavy 25 containers, tanks, or vats are utilized and in these tanks are placed the liquids which are used in the finishing processes. A large variety of fume or vapor emitting liquids are used for this purpose, such as hot water or fuming acids, and since it is not feasible 30 to cover the tanks, as it is necessary to continually change the metal parts which are being finished from one tank to another, the fumes rising from these various tanks escape into the room. When the fumes from 35 a plurality of such tanks are allowed to escape into the room, the room atmosphere very soon becomes saturated therewith. Such an atmosphere is necessarily dangerous to the health of the operators and should 40 be avoided.

According to this invention, the fumes which rise from the tanks or containers are blown across the surface of the liquid in the tank by air which is emitted from a 45 nozzle which extends along the upper edge of one side of said tank. This blast of air together with an air exhaust connected to a funnel-shaped hood mounted on the upper edge of the opposite side of the tank will 50 force all the fumes rising from said tank into the hood from where the fumes can be readily conveyed to a stack exhaust. Thus it will be evident that by the use of this system the atmosphere in a metal finishing 55 room may be maintained clear of fumes.

The invention is illustrated in the accompanying drawings in which:

Figure 1 is a front elevation of a pair of finishing tanks with the associated pipe connections used for exhausting the fumes; 60

Fig. 2 is a section on the line 2—2 of Fig. 1, looking in the direction of the arrows, and illustrates the path of the air currents in the exhaust system.

In the preferred embodiment of the invention, as illustrated in the drawings, a plurality of tanks, such as 3 and 4, in which the finishing fluids are contained are mounted in a series of rows in the finishing room. These tanks contain various solutions, such as hot water, fuming acids, caustic solutions, etc., which are used for cleaning the parts operated on and likewise to obtain the particular finish desired on said parts. To clean iron or steel articles alkaline solutions are used which serve to remove all traces of grease from these parts. In the treatment of iron and steel parts they are generally first immersed in a solution of hot caustic to remove the grease, after which they are rinsed in cold water to remove all traces of the caustic. Following this the parts are dipped in a solution of acid for additional cleaning, after which they are again rinsed in cold water to remove all traces of the acid. Parts which have been submitted to this treatment are thoroughly cleaned and ready for plating and they may then be immersed in a tank containing a plating solution which will give the finish desired. When the parts have been plated they are once more washed in cold water which removes all traces of the plating solution, after which they are again rinsed in hot water which facilitates drying. In the treatment of brass, copper, or other similar parts for the purpose of cleaning and plating different solutions are used. In this process the parts are first cleaned by dipping in a hot solution of caustic, after which they are rinsed in cold water. Following this the parts are dipped in a cyanid solution for additional cleaning, such as taking off scale, etc., after which they are again rinsed in cold water to remove all traces of the cyanid. The parts may then be finished by plating in a warm solution of copper cyanid or other cyanid plating solution and when a sufficient deposit of the finishing metal has been placed on the parts

65 70 75 80 85 90 95 100 105 110

they are washed in cold water and then in hot water to facilitate drying.

It will be observed that all the solutions used in the processes outlined above, with the exception of the cold water, are fume or vapor emitting, and since it is necessary for practical purposes to keep these solutions in open tanks it is essential that vapors and fumes rising therefrom be controlled so that they will not be dissipated in the atmosphere of the plating or finishing room. Connected to the rear end of each one of these tanks is a funnel-shaped exhaust hood 5, the lower end of which extends well into the liquid contained in the tank and the upper end of which protrudes several inches above the top surface of the tank so that the fumes escaping from the tank will readily be directed into the hood. The hood 5 extends along the entire rear edge of the tank and is connected to an exhaust pipe such as 6 which connects with the common exhaust pipe 7 leading to the fan 8. The fan 8 may be of any standard suction producing type and is connected to the stack exhaust pipe 9, into which the air drawn through the hoods 5, the risers 6, and the common exhaust pipe 7 is forced by means of the revolving blades of the fan. Connected to the stack exhaust pipe 9 is the blast supply pipe 10 which terminates in the header or feed pipe 11 from which a series of risers, such as 12, are tapped. Each of these risers is connected to a nozzle 14 which extends along the front edge of the tank and through which a blast of air is blown across the top surface of the tank.

In the operation of the system the revolving blades of the fan 8 will create a suction 40 in the exhaust pipe 6. This will draw air into the hood 5 which will be conducted through the riser 6 and the common exhaust pipe 7 by the fan and into the stack exhaust 45 9. All of the air drawn into the stack exhaust by the fan will not be fed to the stack due to the pipe 10 which acts as a shunt or by-pass, and by virtue of which a small portion of the air in the stack supply pipe 9 will be fed through the riser 12 to the nozzle 50 14. This air shunted out of the stack supply pipe 9 will create a blast through the nozzle 14 which will blow across the surface of the liquid contained in the tank and will, in combination with the suction created by 55 the fan through the hood 5, gather up the fumes rising from the liquid and force them into the exhaust pipe 6. The direction of the circulating air currents is indicated in

Fig. 2 by means of arrows. It will be evident from an inspection of this figure that 60 when the air is circulating through the system, as shown by the arrows, the fumes rising from the tank will not be permitted to rise very far above the surface of the liquid and will not be permitted to escape into the 65 room, since the fan 8 creates a blast and suction across the surface of the liquid which assist one another in gathering the fumes into the hood 5.

Obviously the preferred form of the invention herein described is capable of many variations and applications without departing from its spirit and scope.

What is claimed is:

1. A fume or vapor controlling system 75 comprising in combination, a tank in which fume emitting substances may be placed, means placed along the upper edge of one side of said tank from which a blast of air can be blown across the tank, an exhaust 80 means placed along the upper edge of the opposite side of said tank, and means whereby a stream of air is blown from said first-mentioned means and drawn into said exhaust means said stream of air carrying the 85 fumes into said exhaust means.

2. In a vapor or fume controlling system, the combination with a container, of a nozzle extending along the upper edge of one side of said container, a funnel-shaped exhaust hood mounted on and extending along the opposite side of said container, a fan, 90 a pipe connecting said hood and said fan, and a blast supply pipe connecting said nozzle and said fan, whereby the fumes rising 95 from said container will be controlled by the combined blast and suction and forced into said hood.

3. In a vapor or fume controlling system, the combination with a container, of an 100 exhaust hood extending along the upper edge of one side of said container, an exhaust means including a fan connected to said hood, a stack exhaust pipe terminating at said fan, a blast nozzle extending along the upper edge 105 of the opposite side of said container, a blast supply means interconnecting said stack exhaust and said nozzle, said fan forcing a part of the air from the stack exhaust through said nozzle which in combination 110 with the air drawn into the hood by said fan will force the fumes rising from said container into said stack exhaust.

In witness whereof, I hereunto subscribe my name this 8 day of Aug. A. D., 1916.

GEORGE ALGER PENNOCK.
